UNITED STATES PATENT OFFICE.

OZRO C. LANPHEAR, OF GALESBURG, ILLINOIS.

DESIGN FOR A PIN, BROOCH, OR SIMILAR ARTICLE OF JEWELRY.

46,171.

Specification for Design.

Patented July 28, 1914.

Application filed May 23, 1912. Serial No. 699,330. Term of patent 14 years.

To all whom it may concern:

Be it known that I, OZRO C. LANPHEAR, a citizen of the United States, and a resident of Galesburg, in the county of Knox and State of Illinois, have invented a new, original, and ornamental Design for a Pin, Brooch, or Similar Article of Jewelry, of which the following is a specification, reference being had to the accompanying drawing, forming part thereof.

Figure 1 is an elevation, showing the design as it appears when affixed to the cloth-

ing of the wearer; and Fig. 2, an edge view, disclosing it as when unattached.

Both the imitation of a quill pen and the Greek letters shown thereon are material to the design, and are essential features thereof.

I claim—

The ornamental design for a pin, brooch, or similar article of jewelry, as shown.

OZRO C. LANPHEAR.
